UNITED STATES PATENT OFFICE.

JOHN MAXWELL, OF BROOKLYN, NEW YORK.

DESIGN FOR A COAT, HAT, AND UMBRELLA RACK.

SPECIFICATION forming part of Design No. 17,460, dated July 19, 1867.

Application filed May 16, 1887. Serial No. 238,426. Term of patent 14 years.

To all whom it may concern:

Be it known that I, JOHN MAXWELL, of Brooklyn, Kings county, New York, have invented and produced a new and original Design for Combined Coat, Hat, and Umbrella Racks, of which the following is a specification, reference being had to the accompanying drawing, forming part thereof, and which is a perspective view of a rack embodying my design.

A in the drawing represents a plate of fanciful outline. Projecting upward and outward in an irregular line from the plate A is the arm or hat-holder B, consisting of the double wire or rod c, as shown. Projecting downward and sidewise from the plate A are the rods or

wires d d, which form circles e e below the plate A. The rods d d continue downward from the circles e e and form the hooks f f on their ends, as shown. The circles e e are joined by the cross-rod g.

I claim—

The design for a coat, hat, and umbrella rack herein shown and described, consisting of the plate A, arm B, and rods d d, forming the circles e e and hooks f f, the circles e being between the hooks f and the plate A, as shown.

JOHN MAXWELL.
